TUBE JOINING

John J. Cullen, Brighton, Mass.

Application May 3, 1945, Serial No. 591,766

2 Claims. (Cl. 29—148.2)

(Granted under the act of March 3, 1883, as amended April 30, 1928; 370 O. G. 757)

1

My invention relates to tube joining. More particularly, it relates to the joining of pieces of thin-wall metal tubing in angular relationship to each other. It deals with a method and apparatus for forming the necessary interfitting portions on a main tube and a branch tube for connecting the tubes together in angular relationship.

The method used at present to join thin-wall tubes in angular relationship is a hand method which is both laborious and slow and is, therefore, costly. Furthermore, the hand method necessitates the use of extreme care to attempt to obtain accuracy and often results in non-uniform products.

In joining the tubes, it is the practice to form on the side of the main tube, at the location where the branch tube is to be connected, a suitable boss. On the end of the branch tube which is to be connected to the main tube, a saddle, which is complementary to the boss, is formed. The saddle is fitted over the boss and the main tube and branch tube are suitably secured together, for example, by soldering.

To form the boss on the side of the main tube, it is necessary, with the hand method, to first locate exactly on the side of the main tube, the center of the branch to lead therefrom. The main tube is then held in such a position that the center mark is uppermost and by use of dividers, a circle is scribed on the tube. This circle has a diameter equal to the inside diameter of the branch less the thickness of the metal of the main tube. Then the cup or boss is raised on the main tube. This is accomplished by first drilling a relatively small hole at the center mark which is then filed smooth to prevent cracking during the subsequent metal-working or hammering operation. The drilling operation hardens the surrounding metal, especially if it is copper or copper alloy, and consequently, it is necessary to anneal such metal to facilitate the subsequent metal-working operation. The end of a metal-working pin or bar is then inserted in the drilled opening and by hammering on the side of the pin, the metal is worked upwardly to form a flange around the hole. While hammering, the pin is moved around the edge of the hole to attempt to raise the metal uniformly as the hole is enlarged. This operation causes the raised metal and the adjacent metal of the tube to harden, and it is necessary to anneal the tube from time to time to prevent cracking of the raised metal and distortion of the tube itself. Furthermore, it is necessary to file the edge of

the hole frequently to prevent cracking of the metal. The cup or boss is raised until it has an outside diameter equal to the inside diameter of the branch which will be indicated by reaching the circle scribed on the main tube.

To form the saddle on the end of the branch tube to fit over the boss on the main tube, the following steps are necessary with the hand method. It is first necessary to lay out a template 10 paper pattern for the branch so that it fits the circumference of the main tube. The pattern is then cut out, wrapped around a tube of a size proper for the branch, and the end of the branch is marked along the curved end of the pattern. 15 With a hammer and chisel, the branch is cut off and the burr is filed away. The trimmed branch is placed on the main tube to see that it fits snugly and further filing may be necessary to make it fit properly. Using dividers, an arcuate 20 line parallel to the arcuate end of the branch is scribed at a point spaced a short distance therefrom and is subsequently used as a guide while turning the saddle. Since the cutting operation hardens the adjacent metal, especially if it is 25 copper or copper alloy, it is necessary to anneal the trimmed end of the tube. Then using a bumping hammer or a similar tool, the branch end is worked on the edge of an anvil. The area from the scribed line to the end of the branch 30 is worked outwardly until the saddle of proper shape and size is formed thereon. During the metal-working operation, frequent annealing will be necessary to prevent cracking of the metal.

Before the branch is connected to the main 35 tube, it is usually necessary to place the saddle over the cup or boss to finally check the fit between the saddle and the boss. It is often necessary to further work the boss up into the saddle. The boss must rise well into the saddle before 40 finally smoothing the saddle with a planishing hammer. The surfaces where the boss and saddle meet are then cleaned and fluxed and finally soldered to secure the boss to the main tube. Obviously the hand method discussed above is 45 not readily adaptable to modern production methods and, therefore, is costly. Extreme care must be exercised and it is necessary that the work be performed by skilled labor. Even with such care by qualified labor, the resulting product is not always of the desired accuracy and 50 uniformity.

One of the objects of my invention is to provide a method for forming the desired complementary portions on sections of tubing to join them in angular relationship, the method being

simple, efficient, economical, and readily adaptable to modern production methods.

Another object of my invention is to provide a method and apparatus for forming the desired complementary portions on sections of tubing to join them in angular relationship of such a nature that the forming operations can be performed with ease by unskilled labor.

Another object of my invention is to provide apparatus for forming the desired complementary portions on sections of tubing to join them in angular relationship which is of such a nature that the complementary portions will be accurately formed to predetermined dimensions and will be accurately located at predetermined positions.

Still another object of my invention is to provide a method and apparatus of the type indicated of such a nature that the complementary portions may be so formed that the sections of tubing can be joined to each other at various selected angles.

Various other objects will be apparent from the following description.

According to my invention, the branch-receiving boss is formed on the side of the main tube and the complementary saddle is formed on the end of the branch tube by a novel method and apparatus. The complementary portions on the two tube sections will be accurately formed and located so that the sections can then be connected to each other in the desired angular relationship.

The branch-receiving boss is formed on the side of the main tube by first punching an elongated opening in the form of an ellipse in one side of the main tube. This tube is usually larger than the branch tube although both may be the same size. The opening is disposed at such a point that its center will be at the desired center of the branch to be joined to the main tube. Also, the opening is so disposed that its longer or transverse axis extends longitudinally of the tube and is in the same plane as the axis of the tube. The opening is of a proper size to permit raising of a flange of desired height around it to form a boss having an external diameter corresponding to the internal diameter of the branch which it is to receive. The flange is raised by placing the tube in a female die which has a semi-cylindrical channel for receiving it. At right angles to the channel is a circular boss-forming chamber which is adapted to receive a male die member. This boss-forming chamber is disposed in surrounding relationship to the opening in the tube and has a diameter greater than the transverse axis of the opening in the tube, to permit raising of the flange of desired height around the opening. The male die member is disposed initially within the tube and is then moved at right angles to the axis of the tube through such opening into the chamber of the female die member. The male die member is of such size that it will raise the metal around the opening until it contacts with the wall of the chamber, thereby forming the upstanding flange. Thus, the desired boss is formed on the tube.

The saddle complementary to the boss is formed on the end of the branch tube by first trimming the end to a suitable shape. This shape is such that the end fits the contour of the main tube when the branch is disposed on the main tube at the same angle at which it is to be connected to the main tube. To form the desired flange on the trimmed end of the branch and, thereby, form the saddle, the end is placed in a female die

member. This die member has a cylindrical tube-receiving chamber and a semi-cylindrical channel or chamber disposed at right angles thereto for receiving a male die member. The tube is so disposed in the tube-receiving chamber that its trimmed end extends a selected distance into the semi-cylindrical channel. The male die has a cylindrical forming portion which is complementary to and is adapted to be inserted into the tube-receiving chamber, and a semi-cylindrical forming portion at right angles thereto which is complementary to and is adapted to be forced into the semi-cylindrical channel. When the male die member is inserted into the female die member, the extending end of the tube is engaged by the semi-cylindrical portion of the male die and is bent to the shape of the channel in the female die member. This channel will be of the same shape and size as the outside contour of the main tube to which the branch is to be joined. Thus, the desired saddle is formed on the end of the branch.

After the boss on the main tube and the complementary saddle on the branch tube are formed as indicated, the saddle is positioned over the boss and the two sections are suitably joined together, as by soldering. It will be found that the two portions accurately interfit and will serve to connect the branch to the main tube at the desired angle.

The preferred embodiment of my invention is illustrated in the accompanying drawings wherein similar characters of reference designate corresponding parts and wherein:

Fig. 36 is a view, partly in side elevation and partly in section, illustrating the 45° angle branch positioned on the main tube.

With reference to the drawings, I have illustrated in Figs. 1 and 2 a machine upon which the boss forming dies are adapted to be mounted for actuation. This machine comprises a table 1 upon the upper surface of which is supported a vertical standard 2. The standard 2 is adapted

to support the dies and the actuating means for the dies.

The standard 2 consists of a pair of vertically disposed supporting plates 3. These plates are laterally spaced on the table 1 and each of them has a horizontal flange 4 which rests on the upper surface of the table and which is bolted thereto by bolts 4a. Each of the plates 3 has a lower vertically disposed section 5, which carries flange 10 4, an intermediate forwardly and upwardly curved section 6, and an upper vertically disposed section 7. The lower edge of the section 7, indicated by the numeral 7a, is horizontally disposed at a point spaced a suitable distance above the upper surface of the table. It will be noted in Fig. 2 that the section 7 of the plate and, consequently, the edge 7a is disposed forwardly beyond the front edge of the table. The plates 3 are rigidly joined together by a vertically disposed rear plate 8, which has its ends bolted thereto by the bolts 9 adjacent the upper ends of plates 3, and by a horizontally disposed plate 10 which is bolted by bolts 11 to the extreme upper ends of the plates 3.

Mounted for vertical movement between the plates 3 is a slide 12. This slide has the lower end of a piston rod 13 threaded thereinto, as at 14. The rod 13 extends upwardly through a packing gland 15 into a vertically disposed hydraulic cylinder 16. The cylinder 16 is carried by the horizontal plate 10. The cylinder 16 has a piston 17 disposed therein which is connected to the upper end of the rod 13. Mounted above the hydraulic cylinder 16 is an air cylinder 18. The cylinder 18 has a piston 19 therein which is connected to the piston 17 by a vertical rod 20.

A hydraulic pump 21 is secured to the upper surface of table 1 and may be of any suitable type. The pump is connected by a line 22 to the lower end of the cylinder 16. The flow of fluid to and from the cylinder 16 is controlled by a valve 23 of a suitable type. The valve 23 may be opened to connect the pump 21 to the lower end of cylinder 16 and by actuating the handle 24 of the pump, fluid will be forced into the lower end of cylinder 16 and will force the piston 17 upwardly. This will also force the piston 19 of the air cylinder 18 upwardly. The upper end of cylinder 18 is connected by a line 25 to a valve 26 of a suitable type. The valve 26 will serve to connect the line 25 either to an air pressure line 27 or to a vent 28. At the time the hydraulic piston 17 is moved upward, the valve 26 will be in such a position as to vent the line 25. To move the slide 12 downwardly, the valve 23 is actuated to permit hydraulic fluid to flow from cylinder 16, through line 22, back into the pump 21. At the same time, the valve 26 will be in such position as to connect the pressure line 27 to the line 25. This will cause air to be supplied to the upper end of cylinder 18 and force the piston 19 downwardly.

Hydraulic pressure will move the slide 12 upwardly, which operation will require the greater force, while air pressure will move the slide 12 downwardly and more quickly than the upward movement. Thus, means is provided for moving the slide 12 vertically relative to plates 3. An indicating pointer 12a may be attached to the front side of the slide 12 for cooperation with suitable calibrations on the forward edge of one of the plates 3 to indicate the vertical position of the male die member, as will appear later.

The slide 12 is in the form of an inverted box and a link 29 extends upwardly into the hollow portion thereof. The upper end of the

Link 29 is pivoted at a point midway between the sides of slide 12 by means of a pin 30. The link 29 is provided with a bifurcated lower end 31, as indicated in Figs. 3 and 4. As will later appear, this bifurcated lower end 31 is adapted to receive a cooperating lug formed on a male die member. The end 31 carries a pin 32 which extends through aligned transverse openings 33 formed therein.

A plate 34, which is designed to carry the female die, is adapted to be mounted in horizontal position on the lower edges 1a of the vertical sections 1 of the plates 3. The plate 34 carries on each end an angle member 35 suitably secured thereto. Each angle member cooperates with the top surface of the plate 34 to form a channel for receiving a tongue 36 fastened to the outer surface of each plate 3 in alignment with the edge 1a thereof. Thus, the die-carrying plate 34 may be quickly mounted on the standard 2 by slipping the angle members 35 over the tongues 36. The upper surface of plate 34 will abut edges 1a while the inner edges of angle members 35 will abut the outer surfaces of the plates 3. One of the plates 3 carries a sleeve 37 on its outer surface at a point slightly above the edge 1a. This sleeve 37 carries a pin 38 which may be moved vertically therein and relative to aligning openings formed in the adjacent angle member 35 and tongue 36. When the plate 34 is positioned on the standard 2, the pin 38 will extend into the aligned openings in members 35 and 36 and will serve to lock the plate 34 in position. Thus, horizontal and vertical movement of the plate 34 relative to the standard 2 will be precluded.

The plate 34, as previously indicated, is adapted to carry the female die member of the boss forming die. The die member will be bolted thereto by means of screw bolts 39, as indicated in Figs. 1, 3, and 4. The plate 34 is provided with a large, centrally disposed opening 40 extending completely therethrough. This opening 40 will receive the lower end of link 29 and is adapted to permit the male die member to pass upwardly through the plate, as will later appear. The die carried by plate 34 may be easily removed, by removing bolts 39, and be replaced with a die of different size. On the other hand, if preferred, several of the plates 34 may be provided for carrying different size dies and may be quickly mounted on the standard 2 or be removed therefrom.

Attached to the table 1, substantially midway between the plates 3, and extending outwardly from the table is a horizontal supporting arm 41. This arm carries a split sleeve or collar 42 on its outer end which is in axial alignment with the opening 40 in the plate 34. The sleeve 42 receives a post 43 which may be adjusted vertically therein. The post 43 may be held in any desired position by means of an eccentric locking device 44 which will actuate the split sleeve 42 to grip the post. The upper end of the post 43 carries a horizontally disposed tube supporting the disk 45.

In Figs. 3 to 5, I have illustrated the die members which are used in forming the 90° angle boss on the tube. In this operation I preferably employ the two male die members 46 and 47 and a single female die member 48. The die members 46 and 47 are substantially bell shape. The member 47 is of somewhat greater diameter than the member 46. The female die member is shown in inverted position in Fig. 5. It comprises a tube-receiving channel 49 which is formed on the lower side of the die and extends lengthwise thereof. The channel 49 is substantially semi-cylindrical

and midway between its ends there is formed an opening extending through the top of the die which produces a substantially cylindrical forming chamber 50 disposed at right angles to the channel 49.

Each of the male die members is provided with an upwardly extending lug 51 adapted to be disposed in the bifurcated lower end 31 of the link 29. The lug 51 is provided with a transverse opening for receiving the pin 32. The lug 51 will fit tightly within the end 31 of the link.

As illustrated best in Figs. 3 and 4, the top of the female die member 48 is provided with threaded sockets 52 for receiving the screw bolts 39 carried by the plate 34. It will be apparent that with the female die member 48 secured to the plate 34, with the plate 34 positioned on the standard 2, and with one of the male die members suspended by the link 29, the male die member may be moved upwardly through the chamber 50 of the female die member by raising the slide 12.

In forming a 90° angle boss according to my method and with the apparatus described, I first take a length of main tubing 53 (Fig. 6) and form an elliptical opening 54 therein. This opening 54 may be punched or otherwise formed in the side of the tube. The center of this opening will be located at the center of the branch to extend from the tube 53. The opening 54 will extend lengthwise of the tube with its transverse axis in the same plane as the axis of the tube. The opening 54 is of a predetermined size to permit raising of a flange of desired height around it to form the cylindrical boss 55 (Fig. 7) having an external diameter corresponding to the internal diameter of the branch which it is to receive. The transverse axis of the opening 54 will be of a length equal to the desired internal diameter of the boss 55 less the total height of the two portions of the flange raised at the ends of the opening and which will extend upwardly from the highest point on the tube. The conjugate axis of the opening 54 will be of a length equal to the diameter of the boss 55 less the height of the two portions of the flange raised at the sides of the opening. Thus, a flange can be raised around the opening and this flange will have a level upper edge, as shown in Fig. 7.

To raise the flange in the manner indicated to produce the boss 55, the tube 53 with the opening 54 formed therein is placed upwardly within the channel 49 of the female die 48, the die being carried by the plate 34 which is mounted on the standard 2. The channel 49 has the same contour as the outer surface of the tube 53. The tube is supported by the disk 45 which is adjusted to the proper vertical position. The tube 53 is so positioned that the opening 54 is centered relative to the forming chamber 50 in the die 48, it being understood that a selected area of the metal surrounding the opening 54 will extend inwardly from all directions towards the center of the chamber 50 beyond the wall thereof. Since the diameter of the chamber 50 corresponds to the external diameter of the boss 55 to be formed, and since the size and shape of the opening 54 is preselected as indicated above, the area of the metal extending inwardly beyond the wall of the chamber 50 will be just sufficient to form the upper standing flange which will produce the cylindrical boss 55.

The flange is preferably raised in two successive operations by employing first the male die member 46 (Fig. 3) and then the male die mem-

ber 47 (Fig. 4). To accomplish this, the die member 46 is first positioned in the tube with the lug 51 extending upwardly through the opening 54, as indicated in Fig. 1. The pin 32 is used to attach lug 51 to the link 29. The slide 12 is then raised. This pulls die member 46 upwardly through the opening 54. The tapering side of member 46 engages the edge of opening 54 and gradually raises the surrounding metal and presses it outwardly, in the manner indicated in Fig. 3. The metal is bent without contacting the wall of the forming chamber 50 even as the die is pulled completely through the opening 54 and out of the tube, due to the fact that the largest diameter of die 46 is considerably less than the diameter of chamber 50.

The next operation employs the male die member 47 (Fig. 4) which is of larger diameter, and which is positioned in the tube 53 with its upper end extending through the partly formed boss. The male die member 47 is attached, as before, to the slide 12 which is raised to pull the die upwardly. As the member 47 is pulled upwardly through the partly formed boss, it completes the formation of the boss. The greatest diameter of member 47 is equal to the internal diameter of chamber 50 less twice the thickness of the metal of the tube 53. Consequently, as the member 47 is raised, it will press the metal of the partly formed boss into contact with the wall of chamber 50, as indicated in Fig. 4, and will form cylindrical boss 55, illustrated in Fig. 7. It is preferred to draw the metal, surrounding opening 54 to form the boss in two successive operations rather than in a single operation to prevent cracking of the metal. However, it will be noted that metal extending completely around the opening is raised simultaneously, as distinguished from the hand method where only small sections are raised by successive contact of the pin with the edge of the opening. Better and more uniform results will be obtained with my method.

The boss 55 will serve to connect the branch at right angles to the tube 53. However, it is often desirable to connect branches at other angles. In Figs. 8 to 15, I have illustrated die members for producing a boss for connecting a branch to the main tube at an angle of approximately 45°.

In forming a 45° angle boss, I first take a length of main tubing 56 (Fig. 14) and form an opening 57 therein. The opening 57 will be similar to opening 54 (Fig. 6) except that it will be more elongated since the boss 58 (Fig. 15) to be produced in this instance must be of elliptical form. The boss 58 will have a beveled shoulder 59 at one end and a curved shoulder 60 at the other end formed on the upstanding flange. The elliptical boss 58 will have transverse and conjugate axes corresponding in lengths to those of the elliptical end of the branch which the boss is to receive. Therefore, the corresponding axes of the opening 57 will be the same lengths, less the height of the portion of the flange raised at the ends thereof, as those of the boss. The die members which I employ in forming to the 45° boss include the two male die members 61 and 62, illustrated in Figs. 8 to 12, and a single female die member 63, illustrated in Figs. 8, 9, 10 and 13.

The male die member 61 has the shape illustrated best in Fig. 11. It is of elliptical cross-section and has a vertical lower surface 61a and an inwardly tapering upper forming surface 64. It is provided with an upstanding lug 65 for connecting it to the link 29 depending from the slide 12.

The male die member 62 is considerably longer than the die member 61 although it has a mid-portion of the same width as the mid-portion of die 61. It is of elliptical cross-section and has an inwardly tapering forming surface 66 which extends completely therearound with the exception of one end thereof. At this end there is formed a blunt vertical lower end portion 67 and an upper concave forming surface 68. Attached to the upper top surface of the die 62 is a lug 69 which is used for connecting the die to the link 29.

The female die member 63 is shown in inverted position in Fig. 13. It comprises a tube-receiving channel 70 which is formed on the lower side of the die and extends lengthwise thereof. The channel 70 is substantially semi-cylindrical and is of the same contour as the outer surface of the tube 56. Midway between the ends of channel 70, there is formed an opening extending through the top of the die which produces a forming chamber 71. The forming chamber 71 is mainly of elliptical form with its transverse axis in the same plane as the axis of channel 70. As best shown in Figs. 10 and 13 at one end of the chamber 71 there is a convex surface 72 complementary to the surface 68 formed on the end of the male die member 62. The remaining surface of the chamber 71 is complementary to the surface 66 of the male die 62.

To raise the flange in the manner indicated to produce the boss 58, the tube 56 with the opening 57 formed therein is placed upwardly within the channel 70 of the female die 63, the die being carried by the plate 34 on the standard 2. The tube is supported by the disk 45. The tube 56 is so positioned that the opening 57 is centered relative to the forming chamber 71 in the die 63. A selected area of the metal surrounding the opening 57 will extend inwardly from all directions towards the center of the chamber 71 beyond the wall thereof. Since the size and shape of the chamber 71 correspond to that of the boss 58 to be formed, and since the size and shape of the opening 57 is preselected as indicated above, the area of the metal extending inwardly beyond the wall of the chamber 71 will be just sufficient to form the upstanding flange and will produce the elliptical boss 58.

The flange is preferably raised in two successive operations by employing first the male die member 61 (Fig. 11) and then the male die member 62 (Fig. 12). To accomplish this, the die member 61 is first positioned in the tube 56 with the lug 65 extending upwardly through the opening 57. The lug 65 is attached to link 29 and the slide 12 is then raised. This pulls die member 61 upwardly through the opening 57. The tapering forming surface 64 of the die engages the edge of opening 59 and gradually raises the surrounding metal and presses it outwardly, in the manner indicated in Figs. 8 and 9. As shown in Fig. 8, the width of the mid-portion of the die is the same as that of chamber 71 less the thickness of the metal of the tube at each side thereof. Consequently, the metal will be pressed against the sides of the chamber 71. However, the metal at the end of the opening 57 will not be pressed against the ends of the chamber 71, as shown in Fig. 9, due to the fact that the die member 61 is shorter than the chamber 71, in order to permit upward passage of the male die 61 through the female die 63.

The next operation employs the male die member 62 (Fig. 12). This die member is also posi-

tioned in the tube 56 and has its upper end extending through the partly formed boss. The male die member 62 is attached to link 29. As the die member 62 is pulled upwardly into the partly formed boss and the complementary forming chamber 71, the formation of the boss is completed. However, it will be noted that the male die member 62 merely moves completely into the female die member 63 and not through it. The tapering surface 66 will further bend the metal with which it contacts into forming relationship with the complementary surface of the chamber 71. Also, the concave forming surface 68 will bend the adjacent metal into contact with the complementary convex surface 72. Thus, the elliptical boss 58 will be formed with the inclined portion 59 of the flange formed by cooperating surfaces 66 and 71 and with the convexly curved portion 60 of the flange formed by the cooperating complementary surfaces 68 and 72.

It is to be understood that bosses of other shapes and sizes may be formed by varying the shapes of the die members.

In Fig. 16, I have illustrated a machine upon which the saddle-forming dies are adapted to be mounted for actuation. This machine comprises a supporting table 73. On the top surface of this table 73 at one end thereof is a die-supporting bed plate 74 which may be welded to the table. Also at this end is a U-shaped standard 75 which has its open end directed toward the front of the table. At the opposite end of the table is a vertical standard 76. The standards 75 and 76 are connected together by a top plate 77 which has its one end bolted to member 76 by bolts 78. The opposite end of plate 77 carries an abutment 79, which may be welded thereto, and which abuts the outer surface of standard 75 adjacent its upper end. A similar abutment 80 is welded to the top surface of the table 73 and abuts the outer surface of standard 75 at its lower end. The members 79 and 80 serve as thrust members to prevent outward movement of the standard 75, during the metal-drawing or forming operation, as will later appear. The lower portion of standard 75 has its inner surface abutting the end of plate 74 which will serve to prevent inward movement of standard 75.

The female die unit, illustrated generally by the numeral 81, merely rests on the top surface of the plate 74. Its outer end will engage the standard 75. Adjacent the inner end of the die unit 81, an upstanding pin 82 is provided on the bed plate 74 for preventing inward movement of the unit 81. However, the unit 81 will be free to slide laterally on the plate 74.

On the upper surface of the table 73 at the end opposite to where the plate 74 is disposed, a bed plate 83 is secured in a suitable manner as by welding. This plate 83 has a guideway 84 formed therein and extending longitudinally thereof. This guideway receives suitable guide members 85 that are attached to the lower side of a horizontally disposed hydraulic cylinder 86. Thus, the cylinder 86 is mounted for axial movement. It is adjusted axially by means of a screw 87. This screw 87 has its inner end rotatably connected at 88 to the outer end of cylinder 86 and is threaded through an opening in the standard 76. The outer end of the screw 87 has a handwheel 89 keyed thereto by means of which it may be rotated. Thus, by rotating handwheel 89 the cylinder 86 may be moved longitudinally on the table 73.

The cylinder 86 has a piston 90 slidably

mounted therein. This piston is secured to a piston rod 91 which projects from the cylinder through a packing gland 92. As shown best in Figs. 17 and 18, the end of piston rod 91 is provided with an enlarged disk-like portion 93 which has a reduced cylindrical shank 94 extending therefrom. This shank 94 is adapted to extend into a cylindrical socket formed in the male die member, indicated generally by numeral 96.

A hydraulic pump 97 is provided for moving the piston 90 in the cylinder 86. This pump may be of any suitable type and is operated by a handle 98. A line 99 leads from one end of the cylinder 86 to the pump while a second line 100 leads from the other end of the cylinder to the pump. By actuating a suitable valve 101, the lines 99 and 100 may be selectively connected to the high pressure or low pressure side of the pump. Thus by actuating valve 101 and handle 98, the piston 90 and, consequently, the rod 91 may be moved in the desired axial direction.

The female die unit 81 includes a tube-holding section 102 and a forming section 103, which are adapted to be disposed side by side in the manner illustrated in Figs. 16 and 17. The section 102 is composed of an upper block 104 (Fig. 16) and a lower block 105 which have semi-cylindrical channels of proper contour and size to receive and clamp the tube upon which the saddle is to be formed. The cooperating blocks 104 and 105 which embrace the tube are secured in clamping relationship to the tube by bars 106 which have their lower ends pivoted to blocks 105 and which swing into and out of vertical aligning channels formed on the outer surfaces of the blocks. Each bar has threaded on its upper end a nut 107. By tightening nuts 107 after the bars are swung into operative positions, the two blocks 104 and 105 will be clamped together.

The forming section 103 of the female die unit is adapted to be used in forming the 90° saddle. It is similarly formed of two blocks 108 and 109, as shown best in Fig. 20. These blocks have semi-cylindrical channels therein adapted to cooperate to form a cylindrical chamber 110 in which the tube will be clamped. These blocks are secured together by pivoted bars 111 similar to the bars 106 of the unit 102. The faces of the blocks 108 and 109 are provided with aligning semi-cylindrical channels which cooperate to produce a forming channel 112 having its axis disposed at right angles to the axis of the forming chamber 110. Secured to the outer side of the block 109 and projecting into the channel 112 is a tongue 113.

The male die member 96 for cooperating with the section 103 of the female die member to form the 90° saddle is illustrated in Fig. 9. It comprises a semi-cylindrical forming portion 114 which is complementary to the channel 112 of the female die section 103. On the curved side of the portion 114 midway between the ends thereof and at right angles thereto is a cylindrical shaped forming portion 115 which is complementary to the chamber 110 of the female die section 103. One end of the portion 114 is provided with a channel 116 for receiving the tongue 113 as the male and female dies are moved into cooperative relationship as will later appear.

When the male die member 96 is disposed on the piston rod 91, the cylindrical shank 94 extends into a cylindrical socket 117 (Figs. 17 and 18) which is formed at a central position in the flat surface 118 of the forming portion 114

of the die. To fasten the die to the piston rod, a screw bolt 119 is provided which is inserted through a chamber 120, formed in the portion 115 of the die, and which is threaded into the shank 94.

In forming the 90° saddle, the end of the branch tube 121 is trimmed in the manner illustrated in Figs. 21 and 22. The edge 122 will have such a curvature that it will straddle the main tube 56, to which it is to be joined, when it is disposed at right angles thereto. To form the desired flange on the trimmed end of the branch, and thereby, form the saddle 123 (Figs. 23 and 24), the end of the tube 121 is disposed in the female die unit 81. It is so disposed in the forming portion 103 of the die unit that its trimmed end 123 extends a selected distance into the semi-cylindrical channel 112, as illustrated in Fig. 16. To properly position the end of tube 121 in the die 103 it is merely necessary to align the outermost extremity 122a of edge 122 with the flat face 118 of the die. The portion of the metal extending into the channel 112 will be sufficient to form the flange or saddle 123.

The die unit 81, in which the tube 121 is clamped, will be positioned on the bed plate 74 in the manner illustrated in Fig. 16, the outer end of the tube extending through the member 75. The male die member 96 is mounted on the piston rod 91. The cylinder 86 is adjusted by operating the handwheel 89 until the forming portion 115 of the male die extends into the end of the tube 121 in the female die section 103. The unit 81 is shifted laterally to the necessary extent to permit this. It may be necessary also to initially adjust the die 96 about the axis of rod 91 until the tongue 113 is guided into slot 116. This properly aligns the forming portion 114 of the male die with the channel 112 of the female die. To complete the metal drawing or forming operation, it is merely necessary to properly actuate pump 97 to move piston rod 91 in the proper direction. This will force the male die member completely into the female die member.

As the male die member is forced into the female die member, the cylindrical portion 115 will extend into the end of the tube disposed within chamber 110 and will maintain the tubular shape of the end of the tube. The semi-cylindrical forming portion 114 will engage the projecting trimmed edge 122 of the tube and will bend it into contact with the surface of the channel 112 around the end of chamber 110. Thus, all of the material of the projecting edge 122 is simultaneously bent to form the saddle 123 which will be at right angles to the axis of the tube. Consequently, the saddle will be more accurately and uniformly formed than with the prior art method wherein small sections of the metal are bent successively with a hammer.

As shown in Figs. 34 and 35, the end of the branch tube 121 which has the saddle 123 formed thereon, is placed over the boss 55 of the main tube 53. The external diameter of the boss 55 will be the same as the internal diameter of the tube 121. The saddle 123 will exactly fit the contour of the tube 53 around the boss. The branch tube 121 may be secured to the main tube by soldering, as indicated at 124. The saddle and the boss will accurately interfit and will serve to join the tube sections at right angles to each other.

In forming the 45° saddle for cooperation with

the 45° boss 58 of Fig. 15, I employ the die members illustrated in Figs. 25 to 29 inclusive.

The forming section of the female die unit is illustrated in Figs. 25, 26 and 29. This section 5 125 is made from two parts 126 and 127. These parts are secured together by pivoted rods 128, which cooperate with aligning channels in the two parts in the manner described with reference to the die unit 81. The parts 126 and 127 have 10 semi-cylindrical channels formed therein which cooperate to produce a tube receiving chamber 129 of cylindrical form. One face 130 of the section 125 is flat and vertically disposed. The other face includes an inclined surface 131 and a 15 vertical surface 132 at the lower end thereof. The surface 131 is disposed at an angle of 45°. Joining the surface of the chamber 129 to the surface 131 and the vertical surface 132 is a saddle forming seat 133. This seat 133 inclines 20 inwardly from the surface 132 to its junction with the wall of chamber 129. The seat 133 also inclines inwardly from the surface 131 to its junction with the wall of chamber 129 with the exception of a convex portion 134 at its upper 25 end.

The male die members for forming the 45° saddle are illustrated best in Figs. 25 to 28. I preferably employ a male die member 135 and a male die member 136 which are used successively with 30 the female die member 125. The member 135 is adapted to be attached to the piston rod 91 in the same manner as described with reference to the die member 96 (Fig. 17). This die member 135 comprises a forwardly projecting portion 137, 35 which is of smaller cross-section than that of the tube to be formed, and an upstanding forming portion 138. The top surface 139 of portion 137 is curved to the same contour as the inner surface of the tube to be formed. A forming surface 40 140 is formed on the forward edge of the portion 138 and merges with the surface 139. The surface 140 curves concavely in a vertical plane and convexly in a horizontal plane. Also, it is angularly disposed relative to the horizontal so that 45 it will be complementary to the convex surface 134 of the female die 125, as shown in Fig. 25.

The male die member 136 is similar to the die member 135 but is of larger cross-section. It is provided with a forming surface 141 which is of 50 the same outline as the surface 140 of die 135 and which, consequently, will be complementary to the convex surface 134 of the female die 125, as shown in Fig. 26. However, the forwardly extending portion 142 is of larger cross-section 55 than the similar portion 139 of the die 135. This extension 142 is mainly of cylindrical form and will fit into the tube to be formed, corresponding in contour to the inner surface thereof. The rear end of the die 136 at its lower edge is provided 60 further with an inclined forming surface 143, which merges with the lower curved surface of extension 142. This surface 143 will be complementary to the inclined surface 133 of the female die 125, as illustrated best in Fig. 26.

In forming the 45° saddle, the branch tube 144 is trimmed in the manner illustrated in Figs. 30 and 31. The trimmed edge will fit the contour of the main tube 56, when the branch is positioned at the angle it is to extend therefrom, which in this instance will be at an angle of 45°. Thus the trimmed edge will have the concave curve 146, as shown in Fig. 31, and the convex curve 147, as shown in Fig. 30, at right angles thereto, the curve 147 extending at an angle of 75

substantially 45°. The open end of the tube will, consequently, be of elliptical outline.

The end of the tube 144 is clamped in the female die 125 so that its trimmed end will extend from the forming chamber 129 of the die a sufficient amount to produce the saddle 148 illustrated in Figs. 32 and 33. To properly locate the tube in the female die, it is merely necessary to position the outermost extremity 149 thereof in substantially the same vertical plane as the surface 132 of the die, as shown in Fig. 25.

As shown in Figs. 32 and 33, the final saddle to be produced will be of elliptical form and will be disposed at a 45° angle relative to the axis of the branch. Its flange will include an inclined forward section 150 and a concave rear section 151. It is preferred that this saddle be formed by two successive metal forming or drawing operations to prevent cracking of the metal.

In the first forming operation, the male die 135 is employed. This die is forced into the trimmed end of the tube 144 disposed in the female die 125. The only surfaces of the die 135 which will contact with the trimmed end of the tube will be the surfaces 139 and 140. The surface 139 cooperates with the top of chamber 129 in the female die 125 to maintain the contour of the tube. The surface 140 engages the metal adjacent the end of the tube and bends it upwardly and rearwardly into contact with the complementary forming surface 134 of the female die member. Thus, the complementary surfaces 140 and 134 will produce the curved section 151 of the saddle.

The next forming operation employs the male die 136. In this operation, the die 136 is forced into the partly formed saddle and the female die in which the tube is supported. The extension 142 will serve to maintain the tubular shape of the tube adjacent its end. The surface 141 will cooperate with the surface 134 to maintain the shape of the section 151 of the flange previously formed. The inclined surface 133 of die 136 will engage the extremity 149 of the tube and bend it downwardly into contact with the complementary surface 133 on the female die 125, as shown in Fig. 26. These surfaces 143 and 133 cooperate to produce the inclined section 150 of the saddle.

It is to be understood that saddles disposed at angles other than 45° on the branch may be produced by variations in the shape of the male and female dies.

The branch 144 may now be mounted on the main tube 145 at a 45° angle. This is accomplished by placing the saddle 148 over the boss 58. The curved section 151 of the saddle will interfit with the curved section 60 of the boss. The section 150 of the saddle will cooperate with the inclined section 59 of the boss. The two sections may be secured together, as by solder indicated at 152. The saddle 148 and the boss 58 are accurately formed so that they will properly interfit and so that the branch 144 will be connected to the line 56 at an angle of approximately 45°.

It will be apparent from the above description that I have provided a method and apparatus for forming the necessary complementary portions on sections of tubing to permit joining of the sections in various desired angular relationships. The method is simple, efficient, economical, and readily adaptable to modern production methods. The use of dies in forming the boss and the saddle will result in extreme accuracy and uni-

formity. Consequently, it is not necessary to fit each saddle to a boss with which it is to cooperate. Any saddle will fit any boss for which it is designed to cooperate. The saddles and bosses will not only be accurately formed so that they properly interfit but also will be accurately located so that the branch will extend from the main tube at the proper position. They will also be so formed that the branch and main tube will be disposed in the proper angular relationship.

The invention described herein may be manufactured and used by or for the Government of the United States of America for government purposes without the payment of any royalty thereon or therefor.

Having thus described my invention, I claim:

1. The method of joining a branch tube and a main tube in angular relationship, which comprises forming in the main tube an opening of elliptical outline, the opening being so disposed that its transverse axis extends longitudinally of the tube and is in the same plane as the axis of the tube, the transverse axis of said opening being of a length substantially equal to that of the corresponding axis of the branch less the height of the flange portions to be raised at the ends of said opening, the conjugate axis of the opening being of a length substantially equal to that of the corresponding axis of the branch less the height of the flange portions to be raised at the sides of said opening, simultaneously forcing the entire edge of said opening outwardly to raise a continuous boss around the opening which has a level upper edge, shaping the end of the branch tube to fit the contour of the main tube when disposed at the angle it is to be connected to the main tube, simultaneously forcing the entire edge of the shaped end of the tube outwardly to form a saddle of uniform width which fits the contour of the main tube when disposed at the angle it is to be connected to the main tube, disposing the saddle of the branch tube over the boss of the main tube, and securing the tubes together.

2. The method of joining a branch tube and a main tube in angular relationship, which comprises forming in the main tube an opening of elliptical outline, the opening being so disposed that its transverse axis extends longitudinally of the tube and is in the same plane as the axis of the tube, the transverse axis of said opening being of a length substantially equal to that of the corresponding axis of the branch less the height of the flange portion to be raised at the ends of said opening, the conjugate axis of the opening being of a length substantially equal to that of the corresponding axis of the branch less the height of the flange portions to be raised at the sides of said opening, placing over said opening a female die having an opening therein corresponding to the shape of the boss to be raised on said main tube, inserting a shaped male die into said tube, forcing said male die outwardly through said opening thereby simultaneously forcing the entire edge of said opening outwardly to raise a continuous boss around the opening which has a level upper edge, shaping the end of the branch tube to fit the contour of the main tube when disposed at the angle it is to be connected to the main tube, clamping the end of said tube in a shaped female die with said shaped end projecting therefrom a preselected distance, forcing a shaped male die against said projecting end thereby simultaneously forcing the en-

tire edge of the shaped end of the tube outwardly to form a saddle of uniform width which fits the contour of the main tube when disposed at the angle it is to be connected to the main tube, disposing the saddle of the branch tube over the boss of the main tube, and securing said tubes together.

JOHN J. CULLEN.
